UNITED STATES PATENT OFFICE.

JOHN A. YERK, OF CHICAGO, ILLINOIS, ASSIGNOR TO THE PULLMAN'S PALACE CAR COMPANY, OF SAME PLACE.

DRAW-BAR-SUPPORTING MECHANISM.

SPECIFICATION forming part of Letters Patent No. 643,815, dated February 13, 1900.

Application filed August 8, 1899. Serial No. 726,519. (No model.)

To all whom it may concern:

Be it known that I, JOHN A. YERK, of Chicago, in the county of Cook and State of Illinois, have invented certain new and useful 5 Improvements in Draw-Bar-Supporting Mechanism, of which the following is a specification.

This invention relates to draw-bar-supporting mechanism, and has for its object to provide a construction whereby the wear upon the draw-bar arising from its lateral motion upon its support when in use may be reduced, while at the same time the draw-bar will be 15 yieldingly held in its normal position and returned to that position after lateral displacement.

To this and other ends my invention consists in certain novel features which I will now proceed to describe and will then particularly point out in the claims.

In the accompanying drawings, Figure 1 is a front elevation, partly in section, of a draw-bar, carry-iron, and saddle embodying my invention. Fig. 2 is a plan view of the same. 25 Fig. 3 is a central vertical section through the structure shown in Figs. 1 and 2, the draw-bar being shown in place. Fig. 4 is a front elevation of a modified form of my invention, illustrating one mode of attaching 30 the device to a car-body. Fig. 5 is a side elevation of the same. Fig. 6 is a view similar to Fig. 4, illustrating a modified form of the saddle shown in Fig. 4, and also illustrating the adjustment of the saddle. Fig. 7 is a detail elevation of the saddle shown in Fig. 4 35 detached. Fig. 8 is a front elevation of the spring-guide detached; Fig. 9, a plan view of the same, and Fig. 10 a plan view of the key detached.

40 In draft-gear as ordinarily constructed the draw-bar is free to move laterally to a limited extent at its outer end and is supported so as to permit this movement by means of a carry-iron or stirrup, upon which it directly rests. 45 The friction between the carry-iron and draw-bar results in wear which tends to weaken and destroy the parts, and thereby requires frequent renewal of the draw-bar at considerable expense. My invention has in view 50 more particularly the obviating of these disadvantages, and in carrying out my inven-

tion I employ, in conjunction with a carry-iron or stirrup, a spring-controlled saddle or yoke mounted and traveling on said carry-iron and provided with a seat to receive and support 55 the draw-bar, so that the wear occurs chiefly between the saddle and carry-iron, and the draw-bar is protected therefrom.

In the accompanying drawings I have shown in Figs. 1, 2, and 3 a construction embodying my invention in one form which is particularly adapted for use in center-draft draw-bars. In this construction 1 indicates the carry-iron or stirrup as a whole, which is provided with the horizontal supporting portions 2, by means of which it is suitably connected to the draft-timbers or other portion of the car-body, the vertical portions 3, and the horizontal bearing portion 4. Upon this carry-iron is mounted to slide longitudinally 60 thereof a saddle or yoke 5, comprising a base-plate 6, on which the draw-bar may rest and which in turn rests upon the carry-iron, said saddle being provided with a vertical flange 7 at each end, and said flanges and base-plate 6 forming a seat which receives and holds the draw-bar. The vertical flanges 7 are preferably rounded on their inner faces, as shown, to permit the angular relation of the draw-bar relatively thereto to change without causing 65 binding between the parts. The saddle 5 is provided with downwardly-extending flanges 8, located on each side of the horizontal bearing portion 4 of the carry-iron and preventing lateral displacement of the saddle and 70 carry-iron relatively to each other. Such lateral displacement is still further prevented by the provision of vertical flanges 9, arranged parallel to each other and at right angles to the vertical flanges 7 and adapted to receive 75 between them the vertical portions 3 of the carry-iron when the saddle is moved laterally. It will be understood, of course, that the base-plate 6, and consequently the distance between the vertical flanges 7, is smaller than 80 the distance between the vertical portions 3 of the carry-iron, so as to permit lateral movement of the saddle relatively to the car-body, or, in other words, longitudinal movement of 85 the saddle relatively to the carry-iron.

100 In order to hold the saddle and draw-bar normally in proper position, I employ a spring

or springs acting on the saddle for this purpose and tending to restore the saddle to its normal position when displaced. In the construction shown in Figs. 1, 2, and 3 I employ 5 for this purpose a single spring 10, although a plurality of springs may be employed, as will hereinafter appear. To support this spring, I provide on the under side of the carry-iron 1 a stirrup 11, having vertical arms 12, (shown in dotted lines in Fig. 1,) provided with outwardly-bent extremities 13, by which the stirrup is secured to the under side of the carry-iron, the vertical arms being connected by a cross-bar 14. A guide pin or bolt 15 extends longitudinally through the stirrup, passing through the vertical end pieces 12 thereof, and the spring 10 is coiled around this guide-pin. At each end of the guide-pin there is mounted thereon a thrust-plate 16, having an 15 aperture, through which the guide-pin passes, and a boss 17, which extends into and centers and supports the adjacent end of the spring 10. These thrust-plates are guided between the cross-bar 4 of the carry-iron and the corresponding cross-bar 14 of the stirrup and extend laterally beyond the same, as indicated in Fig. 3, the saddle being provided with shoulders 18, against which the edges of the thrust-plates bear. To this end the lateral 20 flanges 6 of the saddle are extended downward, so as to inclose the thrust-plates and their operating - spring and supporting devices, these extensions being indicated by the numeral 19, so that all these parts of the mechanism are covered and protected.

In practice the draw-bar, which is indicated at 20 in Fig. 3, is placed in the seat formed between the bed-plate 6 and the vertical flanges 7, and when any lateral strain is 25 placed upon the draw-bar, so as to move the same, the saddle will move along with the draw-bar, which will bear against one or the other of the vertical flanges 7. Thus all wear which occurs will be between the bed-plates 40 6 and the carry-iron, and the draw-bar will be protected from such wear. When the saddle is spring-controlled, as in the construction shown and described, the saddle and the draw-bar carried by it will be automatically 45 returned to their normal position after displacement in an obvious manner.

In the construction just described the saddle is adapted for use in connection with a draw-bar of which the neck or that portion 50 which lies within the saddle is normally central relatively to the other parts of the device. It is frequently the case, however, that draw-bars are employed where this portion lies either on one side or the other of the central 55 line of the device, and it is also sometimes desirable to change from one of these types of draw-bar to another. In Figs. 4 and 10 of the drawings I have shown a construction which is adapted to receive any one of these types 60 of draw-bars and to be adjusted so as to properly support and guide either a central draw-bar or one the neck of which lies either to the

right or to the left of the central line. In this construction the carry-iron is substantially identical with that already described, 70 except that it is of greater length. The saddle is also of a construction similar to that shown in Figs. 1, 2, and 3; but there is provided in its lower portion a series of transverse apertures 21, extending through the depending flanges 6 19. In Figs. 4 and 7 three such apertures are shown, while in Fig. 6 two are shown. Instead of employing a single spring 10 I employ two similar springs 22, and I provide upon the guide-pin 15 a sliding 80 sleeve 23, having a centering-block 24, against which the inner ends of the springs 22 bear. The centering-block 24 has an aperture or keyway 25, and the saddle 5 may be so moved that any one of its apertures 21 may be caused 85 to register with the aperture 25 of the centering-block, whereupon the centering-block and saddle may be united by means of a key 26, passing through the registering apertures of both parts. The centering-block being normally held in a central position by means of the springs 22, it is obvious that the saddle may be so set relatively to the centering-block that its seat may be either central, as indicated in Fig. 4, or may lie upon one side or 90 other of the center, as indicated in full and dotted lines in Fig. 6, so that the particular form shown in Figs. 4 and 5 may be so adjusted as to receive any one of the three types of draw-bars mentioned, while that shown in 95 Fig. 6 may be adjusted to receive a draw-bar lying on either one side or the other of the central line.

I do not wish to be understood as limiting myself strictly to the precise details of construction hereinbefore described, and shown in the drawings, as it is obvious that these details may be modified without departing from the principle of my invention.

I claim—

1. The combination, with a laterally-movable draw-bar and a carry-iron, of a saddle interposed between the draw-bar and carry-iron, longitudinally movable on the latter and adapted to engage and move with the draw-bar to prevent wear of the draw-bar on the carry-iron, substantially as described.

2. The combination, with a laterally-movable draw-bar and a carry-iron, of a movable saddle on which the draw-bar rests, said saddle being adapted to slide on and be guided by the carry-iron and being provided with a seat to receive and engage the draw-bar, whereby said saddle moves with the draw-bar and prevents wear between it and the carry-iron, substantially as described.

3. The combination, with a laterally-movable draw-bar and a carry-iron, of a saddle longitudinally movable on the carry-iron, comprising a bed-plate, downwardly-extending flanges between which the carry-iron fits, and upwardly - extending flanges between which the draw-bar fits, whereby the saddle moves with the draw-bar between it and the

carry-iron and prevents wear of the draw-bar, substantially as described.

4. The combination, with a laterally-movable draw-bar and a carry-iron, of a spring-controlled saddle interposed between the draw-bar and the carry-iron and adapted to slide longitudinally with the carry-iron and to engage and move with the draw-bar, whereby the draw-bar is held in and returned to its normal position and wear of the draw-bar on the carry-iron is prevented, substantially as described.

5. The combination, with a carry-iron provided with a depending stirrup, of a saddle mounted and longitudinally movable on said carry-iron, adapted to engage the draw-bar and provided with depending flanges, and spring-controlling mechanism mounted in the depending stirrup and connected with the depending flanges of the saddle to hold this latter in and return it to its normal position, substantially as described.

6. The combination, with a carry-iron, of a saddle longitudinally movable thereon, a

centering-block with which the saddle may be adjustably connected to vary its normal position relatively to the central line of the device, and springs for holding the centering-block normally in a central position and for returning the same to said position when displaced, substantially as described.

7. The combination, with a carry-iron having a depending stirrup, a guide-pin, a centering-block movable thereon, and springs for normally centering said block, said block being provided with a keyway or aperture, of a saddle longitudinally movable on the carry-iron, adapted to engage the draw-bar, and provided with a plurality of transverse apertures, and a key passing through the apertures of the saddle and centering-block to adjustably connect the same, substantially as described.
